UNITED STATES PATENT OFFICE.

KARL S. HOWARD, OF ST. LOUIS, MISSOURI.

POURING LADLE FOR MOLTEN METAL.

Application filed January 14, 1922. Serial No. 529,229.

To all whom it may concern:

Be it known that I, KARL S. HOWARD, a citizen of the United States, residing at St. Louis, Missouri, have invented a certain new and useful Improvement in Pouring Ladles for Molten Metal, of which the following is a full, clear, and exact description, such as will enable others skilled in the art to which it appertains to make and use the same, reference being had to the accompanying drawings, forming part of this application.

My invention relates particularly to the stopper-slide of a pouring ladle for molten metal. Ordinarily, the stopper rod is provided with a stopper at its bottom end and is inclosed, for substantially its entire length, by a series of sleeves composed of refractory material which protect it from contact with the molten metal tapped into the ladle. These sleeves are adapted to slide loosely on the rod and are held in contact endwise with each other by their weight.

When the molten metal enters the ladle and comes in contact with the sleeves, the latter begin to expand, and as they are heated in advance of the stopper rod, they expand more rapidly, moving upward along the rod unless secured at their upper ends against this expansion in which case they are likely to break and crush. If uncured when the metal rises in the ladle to a certain level, the sleeves being relatively light, float and the joints between them open up which allows the molten metal to flow between the sleeves and burn the stopper rod.

My invention has for its object to hold the sleeves sufficiently tightly together to prevent them from floating and separating, and at the same time allowing them to expand, when necessary.

My invention consists in the structure hereinafter described and claimed, reference being had to the accompanying drawing which forms a part of this specification, whereon,

Figure 1 is a vertical section of a pouring ladle, showing my improved stopper slide and its combined operating mechanism in elevation.

Figure 2 is an elevation of the operating mechanism taken at right angles to Figure 1;

Figure 3 is a horizontal section, on en-

larged scale, taken on line 3—3 of Figure 1, showing the tension lever forming part of my invention.

Figures 4 and 5 are views corresponding to Figure 1, showing modifications of my invention.

Like letters and numerals of reference denote like parts in all the figures.

a represents a pouring ladle, broken away, 65 and *b*, a vertically arranged slide stopper rod, to the bottom end of which is fixed a stopper *c*. Surrounding the rod *b* above stopper *c* for substantially the entire depth of the ladle *a* is a series of sleeves *d* composed of refractory material, which contact end to end, and are adapted to slide loosely on rod *b*. The upper end of rod *b* is secured at a suitable distance above the ladle *a* to an arm *e* which extends horizontally outwardly from the side of ladle *a* and its outer end is provided with a vertically dependent bar or bolt 1 provided at its lower end with a block *f*. An upright frame or bracket *g* is fixed to the side of 70 ladle *a*, opposite block *f* by bolts 2. A suitable guide-way 3 is formed in the face of bracket *g*, and in this guide-way 3 a guide plate *h* is adapted to slide vertically. Block *f* is pivoted by a pin 4 to plate *h* 85 as seen in Figure 1, whereby block *f* with arm *e* is movable about its pivot pin 4 for inclining the stopper rod within ladle *a*, as may be required. Block *f* is held in any desired position by a bolt 5 which is 90 fixed at one end to guide-plate *h* and passes through a slotted opening 6 in the lower depending part of block *f* where it is provided with adjusting nuts 5' adapted to bear respectively against the front and rear 95 side of block *f* as shown.

The vertically adjustable guide-plate *h* is held to bracket *g* by a bolt 7 which is fixed at one end to frame *g* and passes through a slotted opening 8 in guide-plate 100 *h* where it is provided with a hand-nut 9 for bearing against and clamping guide-plate *h* to bracket *g* in any desired vertical position.

A horizontal lever *i* between arm *e* and the top of the ladle *a* is pivoted to the underside of arm *e* by a pin 10 to move about its pivot in a vertical plane. The lever *i* has its inner arm 11 preferably forked at the end to straddle stopper rod *b* and bears downward 110 on a washer 12 which is slidable on the rod *b* above the topmost sleeve *d*. The outer

arm 13 of lever *i* has a socket 14 in its underside which seats a coiled spring 15. A lug 16 projects from arm *e* above. Through spring 15 and the closed end of socket 14 5 passes a vertically arranged bolt 17 having its head 17' bearing upward against the bottom end of spring 15, and its free end portion passing through lug 16 and provided with a wing-nut 18 which bears against the 10 upper surface of lug 16 as shown.

By this construction, when spring 15 is compressed against the closed end of the socket 14, an upward pressure on outer arm 13 of lever *i*, and a corresponding downward pressure on arm 11 is produced, which causes the forked end of the latter to press on the topmost sleeves *d* on stopper rod *b*, whereby the sleeves *d* are prevented from separating and floating, but although held 20 closely together, are allowed by the yielding of the spring 15 to expand when subjected to the heat of the molten metal entering the ladle *a*. The pressure imparted to sleeves *d* by the forked end of lever *i*, to effect this 25 result with safety, may be regulated by adjusting the tension of spring 15 by means of wing-nut 18.

It is here noted that spring 15 is located 30 out-side the ladle at the end of lever *i* furthest from rod *b* so that the heat of the molten metal cannot affect the temper of the spring.

If desired, I may substitute for lever *i* and 35 spring 15, a coiled spring 19 surrounding the rod *b* and located between washer 12 and arm *e*, as shown in Figure 4, but this is too close to the molten metal to be satisfactory generally and is likely to be used as an 40 emergency measure only.

40 In lieu of coiled spring 19, I may use a series of flexible cupped discs 20 surrounding rod *b* between washer 12 and arm *e*, as seen in Figure 5.

I claim:

45 1. In a ladle stopper, a rod, a plurality of rod enclosing sheathing elements arranged end to end, and yielding means remote from

said rod and elements, and connecting members whereby said means are adapted to maintain contact of said elements with each other.

2. In a ladle stopper, a rod adapted to be inserted in the ladle, a carrier adapted to hold said rod, sectional sheathing elements 55 protecting said rod from the contents of the ladle, and means mounted on said carrier at a point substantially to one side of the ladle and adapted to yieldingly maintain the contact of said elements with each other.

3. In a ladle stopper, a carrier adapted to 60 be positioned outside of a ladle, an arm thereon adapted to extend over the interior of the ladle, a downwardly extending stopper rod on the end of said arm, elements surrounding said rod and contacting with 65 each other, a member engaging the top one of said elements and extending outwardly from the ladle, and yielding means engaging the outwardly extending portion of said member and through the latter exerting 70 downward pressure on said elements.

4. In a ladle stopper, a carrier adapted to 75 be positioned outside of a ladle, an arm thereon adapted to extend over the interior of the ladle, a downwardly extending stopper rod on the end of said arm, elements surrounding said rod and contacting with each other, a lever fulcrumed on said arm between its ends with one end engaging the 80 top one of said elements and the other end extending outwardly from the ladle, and yielding means mounted on said carrier and tending to raise the latter mentioned end of said lever.

5. In a ladle stopper, a rod, sheathing elements movable on said rod and adapted to 85 contact with each other, and adjustable yielding means remote from said rod and elements for maintaining said elements in contact with each other.

In testimony whereof I hereunto affix my signature this 7 day of Jan., 1922.

KARL S. HOWARD.
